UNITED STATES PATENT OFFICE.

RAYMOND B. GLIDDEN, OF KEWANEE, ILLINOIS, ASSIGNOR TO KEWANEE IMPLEMENT COMPANY, OF KEWANEE, ILLINOIS, A CORPORATION OF ILLINOIS.

WATERING APPARATUS.

1,287,671.

Specification of Letters Patent.

Patented Dec. 17, 1918.

Application filed May 9, 1918. Serial No. 233,457.

To all whom it may concern:

Be it known that I, RAYMOND B. GLIDDEN, a citizen of the United States, residing at Kewanee, in the county of Henry and State 5 of Illinois, have invented certain new and useful Improvements in Watering Apparatus, of which the following is a specification.

My invention concerns certain features of 10 novelty and advantage in watering-applications of the fountain or reservoir type operating on the vacuum principle. Its prime or leading object is to provide an apparatus of this general type and style which, while 15 structurally simple, inexpensive to manufacture, and unlikely to become damaged in shipment or service, is, nevertheless, strong, firm, and rigid.

One of its salient features is the employment 20 of the water-supply-tank in such a way as to strengthen and reinforce its own supporting frame. The latter is also assisted from becoming distorted or displaced during the performance of its supporting function by the incasing housing or shell. By 25 taking advantage of both of these strengthening and bracing means, the tank supporting framework may be made less expensive than usual and the ordinary diagonal or corner 30 braces may be omitted.

Various other features of benefit, utility, and superiority will become apparent to those skilled in this art from a consideration of a preferred embodiment of the invention 35 illustrated in the accompanying drawing and described in detail below.

In these drawings, forming a part of this specification, and throughout the various views of which like reference characters refer to the same parts,

Figure 1 is a perspective view showing the skeleton supporting frame, the water supply-tank, and the means fastening the two together, and

Fig. 2 is a vertical cross-section through the complete appliance illustrating the incasing housing or shell and the trough.

The appliance includes a tank-supporting skeleton-frame comprising four, corner, upper 50 right angle-bars or posts 10, 11, 12, and 13, the lower ends of which are fastened together by two longitudinal angle-bars 14 and 15 and a pair of flat end-bars or strips 16 and 17. This bottom of the frame is 55 equipped with a sheet-metal pan 18 resting

on the inturned flanges of the two opposite angle-bars 14 and 15, the rim or wall of the pan being riveted, if desired, to the upstanding portions of the four bars constituting such bottom. The top of the frame is composed of two longitudinal angle-bars 19 and 20 riveted to the corner-posts, each of such bars having a top, horizontal, inturned flange, as is clearly illustrated in Fig. 2, The top of this frame also comprises two flat 60 end bars 21 and 22, thus giving to the frame a rectangular top opening adapted to receive a portion of the cylindrical water supply-tank. This supporting-frame is not provided with any diagonal or corner braces, 65 and by reason of the other features of the structure of the appliance as a whole, the frame may be made weaker as to its structural elements and the employment of the fastening rivets, than would otherwise be 70 possible. As is clearly shown, the connections of the various bars one with another at the corners of the frame are made with single rivets only, whereby the frame of itself is not necessarily effectively prevented 75 from possibly becoming distorted out of shape, double riveting or bracing of some kind ordinarily being required to adequately stiffen such a frame against distortion.

The sheet-metal cylindrical water-reservoir or supply tank 23 is provided with inwardly-disposed stiffening corrugations or ribs 24, 24, and at its opposite ends it has outstanding, circular, marginal, seam rims or flanges 25, 25. This tank or barrel is disposed horizontally and fits partially in the top of the frame, being supported by the bars 19 and 20 and it completely fills the rectangular opening of the frame, preventing the skewing or twisting of the frame out 90 of shape. Stated otherwise, the tank, although supported by the frame, performs its function of maintaining the latter in proper form and shape to preserve the maximum strength relations of its component 95 parts or elements.

In order to prevent the tank from becoming displaced with relation to the frame during transportation, and to still further stiffen and brace the duplex structure as a 105 whole, I provide at each corner of the frame a metal strap 26 riveted at its lower end to the frame and at its upper end to the corresponding marginal seam rim 25 of the tank or water container.

The appliance also comprises a sheet-metal shell or casing 30 fitted over the tank and frame and having a substantially semi-cylindrical upper part 31 over and spaced away 5 from the corresponding portion of the tank to provide an air jacket or insulation between the two. The lower section or half 10 32 of such housing is rectangular in shape and snugly or closely fits around the frame, 15 thereby coöperating with the tank in preventing distortion or twisting of the frame. It should be clear, therefore, that the tank and the housing preclude the possibility of the frame becoming forced out of shape, 20 misshapen, or deformed; the tank by coöperating with the frame internally, the housing or casing by co-acting therewith externally.

At its top, this cylindrical sheet-metal 25 water-container 23 is equipped with a filling pipe or tube 33 which extends upwardly and out through a registering aperture in the housing, being provided outside or above the latter with a removable top or closure 30 34. The water of the tank is delivered from its bottom through a pipe 35, supplied with a controlling valve 36, to a trough 37 with an inclined hood 38; both demountably secured on the housing beneath 35 the tank; the water level in the trough being maintained substantially constant by reason of the gradual feeding from the tank on the well-understood vacuum principle. The housing may, if desired, be bolted to the frame, and to remove it such bolts are taken out and the trough demounted therefrom, 40 whereupon the shell or casing can be readily lifted off.

To those skilled in this art it will be apparent 45 that this device is simple in structure, but possesses adequate strength, being reinforced, stiffened, and strengthened by the correlation and coöperation of its different elements in the manner indicated. It possesses substantial water capacity without being objectionably high, the disposition 50 of the barrel or tank lengthwise of the frame facilitating the accomplishment of this result, as well as rendering possible the fitting of a rectangular section thereof in the top of the frame.

The invention is not limited and restricted to the precise and exact structural elements set forth, because these may be varied 55 in minor details without departure from the substance and heart of the invention, and without the sacrifice of any of its substantial benefits and desirable capabilities. It will be understood, therefore, that the invention 60 is susceptible of a variety of embodiments all incorporating and including its main structural and functional advantages.

I claim:

1. In a watering-appliance of the character described, the combination of a skele-

ton-frame having an open top bordered by bars of the frame, a water supply-tank having its lower portion snugly fitted in said open top and supported by at least some of said frame bars bordering said top opening, 70 a trough, means to conduct the water of said tank to said trough, and a casing housing said tank, frame, and trough, substantially as described.

2. In a watering-appliance of the character described, the combination of a skeleton-frame having a top with a rectangular opening bordered by bars of said frame, a substantially-horizontally disposed cylindrical water supply-tank having its lower 80 portion snugly fitted in said open top with its curved wall resting on and supported by at least some of said frame bars bordering said top opening; said tank preventing said frame top from becoming distorted out of 85 rectangular shape, a trough; means to conduct the water of said tank to said trough, and a casing housing said tank, frame, and trough, substantially as described.

3. In a watering-appliance of the character described, the combination of a substantially-unbraced skeleton-frame having a top with a rectangular opening bordered by bars of said frame, a cylindrical water supply-tank horizontally disposed with its lower 95 portion snugly fitted in said top opening and supported by at least some of said frame bars bordering said top opening, said tank preventing said frame top from becoming distorted out of rectangular shape, means to fasten said tank to said frame, a trough, means to conduct the water of said tank to said trough, and a casing housing said tank, frame, and trough, substantially as described. 100

4. In a watering-appliance of the character described, the combination of a skeleton-frame having a top with a rectangular opening, a cylindrical water supply-tank adapted to snugly fit in said open top and supported by said frame, said tank preventing said frame top from becoming distorted out of rectangular shape, a trough, means to conduct the water of said tank to said trough, and a casing housing said tank, 110 frame, and trough, and closely fitting over said frame, thereby preventing distortion or twisting thereof, substantially as described.

5. In a watering-appliance of the character described, the combination of a skeleton-frame having a top with a rectangular opening bordered by bars of said frame, a horizontally-disposed cylindrical water supply-tank having its lower portion snugly fitted in said top opening and supported by 120 at least some of said frame bars bordering said top opening, said tank preventing said frame top from becoming distorted out of rectangular shape, means to fasten said tank to said frame, a trough, means to conduct 125

the water of said tank to said trough, and a casing housing said tank, frame, and trough and closely fitting over said frame preventing distortion or twisting thereof, substantially as described.

6. In a watering-appliance of the character described, the combination of a substantially-unbraced skeleton-frame having a top with a rectangular opening bordered by 10 bars of said frame, a horizontally-disposed cylindrical water supply-tank having its lower portion snugly fitted in said open top and supported by at least some of the frame bars bordering said top opening, said tank 15 preventing said frame-top from becoming distorted out of rectangular shape, said tank also at each end having an extended circular rim, means to fasten said rims to said frame, a trough, means to conduct the water of said 20 tank to said trough, and a casing housing said tank, frame, and trough, and closely fitting over said frame preventing distortion or twisting thereof, substantially as described.

25 7. In a watering-appliance of the character described, the combination of a skeleton-frame, a cylindrical water-supply-tank supported in horizontal relation on said frame, means fastening said tank to said 30 frame, a trough, means to deliver the water of said tank to said trough, a sheet-metal housing incasing said tank, frame, and trough, said housing having a substantially-semi-cylindrical upper portion fitting over 35 the corresponding part of said tank and a substantially-rectangular lower portion fitting over the lower part of the tank and the supporting-frame, substantially as described.

8. In a watering-appliance of the character described, the combination of a skeleton-frame, a cylindrical water-supply-tank supported in horizontal relation on said frame, said tank at each end having an extended circular rim, means fastening said 40 rims to said frame, a trough, means to deliver the water of said tank to said trough, a sheet-metal housing incasing said tank, frame, and trough, said housing having a substantially-semi-cylindrical upper portion 45 fitting over the upper part of said tank and a substantially-rectangular lower portion 50 fitted over the lower part of the tank and the supporting-frame, substantially as described.

55 9. In a watering-appliance of the character described, the combination of a skeleton-frame having a top with a rectangular opening, a horizontal cylindrical water supply-tank snugly fitted in said open top and supported by said frame, said tank preventing said frame top from becoming distorted out of rectangular shape, said tank at each end having an extended circular rim, means to fasten said rims to said frame, a trough, 60 means to conduct the water of said tank to said trough, and a sheet-metal housing incasing said tank, frame, and trough, said housing having a substantially-semi-cylindrical upper portion fitting over the corre- 65 70 sponding part of said tank and a substantially-rectangular lower portion incasing the lower part of said tank and closely fitting over the frame thereby preventing distortion or twisting of the latter, substantially 75 as described.

RAYMOND B. GLIDDEN.
